UNITED STATES PATENT OFFICE.

WILLIAM JOHNSTON AND CHARLES H. ROMER, OF DAYTON, OHIO.

CORE-MAKING DEVICE.

1,149,448.

Specification of Letters Patent.

Patented Aug. 10, 1915.

Application filed October 9, 1914. Serial No. 865,864.

To all whom it may concern:

Be it known that we, WILLIAM JOHNSTON and CHARLES H. ROMER, citizens of the United States, residing at Dayton, in the 5 county of Montgomery and State of Ohio, have invented certain new and useful Improvements in Core-Making Devices, of which the following is a specification.

This invention relates to new and useful 10 improvements in core making devices.

The principal object of our invention is to provide a simple, cheap and efficient device for making a plurality of cores in approximately the time it takes to produce 15 one. Not only is it possible to make a large number of cores with our improved device, but the mechanism of the latter may be readily set to produce cores of a desired size, the latter being properly vented by 20 penetrating means of an equally unique character.

Other important and incidental objects 25 will be brought out in the following specification and particularly set forth in the subjoined claims.

The preferred form of embodiment of our invention is illustrated in the accompanying drawings, of which—

Figure 1 is a top plan view of our improved core-making device. Fig. 2 is a side elevation of the device, showing the same in readiness to make several cores. Fig. 3 is a detail view of a portion of the device, showing in particular one function of the 35 locking means. Fig. 4 is a sectional view of a portion of the device, showing one of the vent rods after it has been forced through a plunger and core-making barrel. Fig. 5 is a perspective view of one of the locking 40 devices. Fig. 6 is an elevational view of a cylinder for setting the mechanism of the device to a position to make cores of a desired size, and Fig. 7 is a sectional view taken through the device shown in Fig. 2 45 along the longitudinal axis of the left-hand rod which extends below the core barrels, and at right angles to the plane of the paper.

Throughout the specification and drawings, similar reference characters denote corresponding parts.

In a detailed description of our invention, 1 designates a longitudinal member preferably constructed of metal. Extending 55 through the middle portion of the member

1, and firmly secured therein, is a plurality of core barrels or cylinders 2, preferably of similar size and shape and disposed in parallel relation to each other. Rigidly secured to, and projecting upwardly from the longitudinal member 1, one on each side of the longitudinal row of core barrels 2, are rods 3 which loosely pass through bores in a longitudinal member 4 similar to the longitudinal member 1. The upper ends of the 60 rods 3 extend loosely through vertical cylinders 5 whose lower ends fit tightly within the bores through which the rods 3 loosely pass. Surrounding the lower portions of the rods 3, are coil springs 6, the lower ends 70 of which rest on the longitudinal member 1 while the upper ends thereof extend loosely into the cylinders 5 and engage shoulder portions 6^a in the latter. By means of these springs 6 the longitudinal members 1 and 4 75 are normally held apart. (See Figs. 2 and 3).

Passing through the longitudinal member 4, and firmly secured therein by means of screws 7, are the stems 8 of plungers 9. 80 These plungers are so disposed above the core barrels 2 that they will enter and occupy different positions in the latter when the longitudinal member 1 is moved toward the longitudinal member 4. The plungers 85 9 and stems 8 thereof are cast hollow to permit vent rods 10 to loosely pass therethrough into the core barrels 2. These vent rods 10 firmly depend from a bar 11, each end of which is bored out to loosely receive 90 a cylinder 5. Surrounding the cylinders 5, between the longitudinal member 4 and bar 11, are coil springs 12 which normally hold the bar 11 a sufficient distance above the member 4 to keep the vent rods 10 above the 95 lower ends of the plungers 9. However, the bar 11 may be depressed against the tension of the springs 12, to force the vent rods 10 completely through said plungers for a purpose to be hereinafter explained. (See 100 Fig. 4.)

When the longitudinal member 1 is in its lowermost position with reference to the member 4, the rods 3 will project a sufficient 105 distance above their respective cylinders 5 to receive removable collars 13. The collars 13 and rods 3 are so constructed that when the former are placed in a certain position on the latter, a bore will extend through both to receive a pin 15 by means of which 110

the collars 13 may be firmly secured to said rods.

Adapted to be readily slipped on the rods 3, between the collars 13 and cylinders 5, are sleeves or cylinders 16 of different lengths for a purpose to be hereinafter described. When in position on the rods 3, these sleeves 16 will rest upon the flanged portions 17 of the cylinders 5, said flanged portions also serving to limit the movement of the bar 11 when the latter is forced upwardly by the springs 12. (See Figs. 1, 2 and 6.)

For the purpose of supporting the device 15 in an upright position, the following construction is provided: Projecting from, and integral with the longitudinal member 4, one on each side of the lower end of the left hand cylinder 5, are bosses 18. Similar 20 bosses 19 project from the longitudinal member 4 opposite the lower end of the right hand cylinder 5. Secured in a vertical bore in each one of the bosses 18, by means of a countersunk screw 20, is a rod 21 which extends downwardly a slight distance below the lower ends of the core barrels 2. A similar rod 22 is secured in a vertical bore in each one of the bosses 19, by means of a countersunk screw 23; the rods 21 forming 25 with the rods 22, four legs upon which the device is supported in an upright position. Each pair of these legs is spaced a sufficient distance apart to permit the longitudinal member 1 to be readily moved up and down 30 between them.

By means of the following construction, the longitudinal member 1 may be locked in an adjusted position, or, in other words, its movement may be limited in either direction 40 with reference to the longitudinal member 4: Provided on two of the rods 21 and 22 which are on the same side of the longitudinal member 1, are collars 24 adjustable on said rods by means of screws 25. Each collar 24 has a cylindrical extension 26 which also slides over the rods 21 and 22 and to the lower end of which is rigidly secured a cap 27 after said extension loosely passes through an aperture 28 in a latch 29. Each 45 latch 29 has a tongue portion 30 adapted to be turned into the path of the longitudinal member 1 by an upright arm 31 integral with the other end of said latch (see Figs. 4 and 5). By unloosening the screws 25, the collars 24 may be moved along the rods 21 and 22 to a position thereon in which it is desired to turn the tongue portion 30 of the latch 29 into the path of the longitudinal member 1 during either its upward 50 or downward movement. In Fig. 2 the tongue portion 30 is in a position which limits the upward movement of the member 1, while in Fig. 3 it is shown in a position which limits the downward movement of 55 said member. The longitudinal member 1

has concave recessed portions 32 and 33 to permit it to readily pass the collars 24 during its upward and downward movement.

In operation, the ends of the longitudinal members 1 and 4 are firmly gripped by the 70 hands of the operator, and the member 1 moved toward the member 4. When the member 1 has been drawn upwardly a desired distance, the collars 24 may be moved along the rods 21 and 22 to a position in 75 which the tongue portions 30 of the latches 29 may be forced below the member 1 to hold it in its elevated position against the tension of the springs 6. (See Fig. 3). By withdrawing the pins 14, the collars 13 may 80 then be removed from the upper ends of the rods 3 to permit a cylinder 16 of the desired length to be slipped on the upper end of each of said rods, after which the collars 13 may again be pinned to the rods 3 above the 85 cylinders 16. As the cylinders 16 rest upon the cylinders 5, they will form a barrier to the downward movement of the collars 13, and as the latter are pinned to the rods 3 which are attached to the member 1, said 90 member will be held in an elevated position by said cylinders 16. The tongue portions 30 of the latches 29 may now be moved from under the member 1, as the only function of said levers in this instance is to hold 95 said member in an elevated position until the cylinders 16 can be inserted or removed. Since the core barrels 2 are attached to the member 1 and the plungers 9 to the member 4 by which the cylinders 5 are supported, 100 it will now be observed that the length of the cylinders 16 will determine the distance the member 1 dare not go below the member 4, or the highest position of the plungers 9 in the core barrels 2. Thus it is possible by 105 means of the cylinders 16, to so set the plungers 9 within the core barrels 2 as to produce cores of a desired length. When the plungers 9 have been so set, the collars 24 are moved along the rods 21 and 22 to a 110 position in which the tongue portions 30 of the latches 29 may be moved into contact with the upper surface of the member 1, as shown in Fig. 2. The device is then firmly 115 grasped by the hands and the core barrels 2 thrust down one or more times upon the wet sand, whereupon the latter will be forced tightly into said barrels against the plungers 9 to form cores 34. The force of the impact of the core barrels 2 upon the wet sand will 120 not move the member 1 upwardly beyond its set position, because such a movement will be restrained by the tongue portions 30 of the latches 29. After the cores have been formed in the barrels 2, the bar 11 is forced 125 downwardly by the hand or hands, to push the rods 10 through the plungers 9 and into the cores 34 a desired distance for the purpose of forming vent holes in the latter, after which said bar will be returned to its 130

normal position by the springs 12. (See Figs. 2 and 4). To remove the cores 34, the tongue portions 30 of the latches 29 are moved out of the path of the member 1 and 5 the latter elevated, whereupon the plungers 9 will force said cores out of the lower ends of the barrels 2.

It will now be seen that by the use of our improved device, a plurality of cores may 10 be made quickly and efficiently, and properly vented and removed.

We do not wish to be limited to the details of construction and arrangement herein shown and described, and any changes or 15 alterations may be made therein to suit different conditions of use.

Having described our invention, we claim:

1. A core-making device comprising a plurality of hollow members, plungers movable in said members, compressible means for varying the positions of the plungers in said members, and means for locking said compressible means in an adjusted position, substantially as described.

2. A core-making device comprising a plurality of hollow members, plungers movable in said members, compressible means for collectively varying the positions of the plungers in said members, penetrating devices, and means for forcing said devices through the plungers to produce vent holes in the cores, substantially as described.

3. A core-making device comprising a plurality of hollow members, plungers movable in said members, compressible means for varying the positions of the plungers in said members, means for locking said compressible means in an adjusted position, penetrating devices, and means for collectively forcing said devices through the plungers to produce vent holes in the cores, substantially as described.

4. A core-making device comprising hollow members arranged in longitudinal alignment, plungers movable in said members, compressible means for varying the positions of said plungers in their respective hollow members, devices for locking said compressible means in an adjusted position, 50 rods adapted to loosely pass through said plungers, and means for collectively forcing said rods through the plungers to produce vent holes in the cores, substantially as described.

5. A core-making device comprising a plurality of barrels, plungers movable in said barrels, a longitudinal member to which said barrels are secured in vertical alignment with each other, another longitudinal member supporting said plungers in similar alignment, upright members adapted to guide said longitudinal members during a movement toward and away from each other to vary the positions of said plungers in 60 their respective hollow members, and a de-

vice for limiting the movement of said barrel supporting member in either direction, substantially as described.

6. A core-making device comprising a plurality of barrels, plungers movable in said barrels, a longitudinal member to which said barrels are secured in vertical alignment with each other, another longitudinal member supporting said plungers above said barrels, upright members adapted to guide 75 said longitudinal members during a movement toward and away from each other to vary the positions of said plungers in their respective hollow members, and detachable means carried by said upright members to limit the movement of said barrel-supporting member from the plunger-supporting member, substantially as described.

7. A core making device comprising a plurality of barrels, plungers movable in said barrels, a longitudinal member to which said barrels are secured in vertical alignment, another longitudinal member supporting said plungers above said barrels, upright members carried by the barrel-supporting member passing loosely through the plunger-supporting member, caps on the tops of said upright members above the plunger-supporting member, and means insertible between said caps and the latter 90 member to limit the movement of the barrel-supporting member from said plunger-supporting member, substantially as described.

8. A core-making device comprising a plurality of barrels, plungers movable in said barrels, a longitudinal member to which said barrels are secured in vertical alignment, another longitudinal member supporting said plungers above said barrels, rods carried by the barrel-supporting member 100 passing loosely through the plunger-supporting member, removable caps carried by the tops of said rods above the plunger-supporting member, and cylinders insertible on said rods between said caps and the latter 110 member to limit the movement of the barrel-supporting member from said plunger-supporting member, substantially as described.

9. A core-making device comprising a plurality of barrels, plungers movable in said barrels, a longitudinal member from which said barrels depend, another longitudinal member supporting said plungers above said barrels, rods secured to the barrel-supporting member passing loosely through the plunger supporting member, cylinders mounted on said last named member through which said rods also pass, caps removably mounted on said rods above said cylinders, and sleeves adapted to be inserted on said rods between the caps and cylinders to limit the movement of the barrel-supporting member away from the plunger-supporting member, substantially as described.

10. A core-making device comprising a plurality of barrels, plungers movable in said barrels, a longitudinal member from which said barrels depend, another longitudinal member supporting said plungers above said barrels, rods secured to the barrel-supporting member passing loosely through the plunger supporting member, coil springs encircling said rods between said members to hold them normally apart, cylinders mounted on said last named member through which said rods also pass, removable collars secured to said rods above said cylinders, and sleeves adapted to be inserted on said rods between the caps and cylinders to limit the movement of the barrel-supporting member away from the plunger-supporting member, substantially as described.
15. 11. A core-making device comprising a plurality of barrels, plungers movable in said barrels, a longitudinal member from which said barrels depend, another longitudinal member supporting said plungers above said barrels, rods secured to the barrel-supporting member passing loosely through the plunger-supporting member, to guide the latter during a movement toward or away from the plunger-supporting member, and adjustable latching means carried by said last named member to limit the movement of said barrel-supporting member in either direction, substantially as described.
20. 12. A core-making device comprising a plurality of barrels, plungers movable in said barrels, a longitudinal member from which said barrels depend, another longitudinal member supporting said plungers above said barrels, rods secured to the barrel-supporting member, passing loosely through the plunger-supporting member to guide the latter during its movement toward the plunger-supporting member, bosses projecting from one side of said last named member, rods projecting downwardly from said bosses, collars adjustably movable on said rods, and latches pivotally carried by said collars to engage the upper or lower surface of said barrel-supporting member, substantially as described.
25. 13. A core-making device comprising a plurality of barrels, hollow plungers movable in said barrels, a longitudinal member from which said barrels depend, another longitudinal member supporting said plungers above said barrels, rods secured to the
- barrel-supporting member, passing loosely through the plunger-supporting member, cylinders mounted on said last named member through which said rods also pass, rods adapted to pass through said hollow plungers into their respective core barrels, and means guided by said cylinders for collectively forcing said last named rods through said plungers, substantially as described. 60
30. 14. A core-making device comprising a plurality of barrels, hollow plungers movable in said barrels, a longitudinal member from which said barrels depend, another longitudinal member supporting said plungers above said barrels, rods secured to the barrel-supporting member, passing loosely through the plunger-supporting member, to guide the latter during its movement toward the plunger-supporting member, upright guides secured to said last named member, a bar having a vertical movement directed by said guides, and a plurality of rods depending from said bar and adapted to be forced 70 by the latter through the hollow plungers, substantially as described. 75
35. 15. A core-making device comprising a plurality of barrels, hollow plungers movable in said barrels, a longitudinal member from which said barrels depend, another longitudinal member supporting said plungers above said barrels, rods secured to the barrel-supporting member, passing loosely through the plunger-supporting member, cylinders mounted on said last named member through which said rods also pass, a bar having end portions vertically slidable upon said cylinders, a plurality of rods depending from said bar and adapted to be forced 80 by the latter through said hollow plungers, and coil springs encircling said cylinders between said bar and the plunger-supporting member, to normally hold said rods above the lower ends of said plungers, substantially as described. 90
40. 16. A core-making device comprising a plurality of barrels, hollow plungers movable in said barrels, a longitudinal member from which said barrels depend, another longitudinal member supporting said plungers above said barrels, rods secured to the barrel-supporting member, passing loosely through the plunger-supporting member to guide the latter during its movement toward the plunger-supporting member, bosses projecting from one side of said last named member, rods projecting downwardly from said bosses, collars adjustably movable on said rods, and latches pivotally carried by said collars to engage the upper or lower surface of said barrel-supporting member, substantially as described. 95
45. 17. A core-making device comprising a plurality of barrels, hollow plungers movable in said barrels, a longitudinal member from which said barrels depend, another longitudinal member supporting said plungers above said barrels, rods secured to the
